MACHINE FOR CAPPING TACK HEADS

Nils H. Anderson, Shelton, Conn., assignor to
The Shelton Tack Co., Shelton, Conn., a cor-
poration of Connecticut

Application June 12, 1936, Serial No. 84,792

8 Claims. (Cl. 10—158)

My present invention relates to capping machines, and more particularly to an improved machine for applying and attaching caps of relatively thin material to the heads of tacks.

It has become customary in recent years to cover the heads of tacks, and particularly the ordinary well known metal thumb tack, with a cover of thin sheet material such as celluloid, "Cellophane" or the like, such covering material being of any color, and giving to the finished article an attractive and ornamental appearance. Such covering material, regardless of the character of the material of which the same is made, may be transparent, or more ordinarily translucent, and such material when at ordinary temperature is relatively brittle. The brittleness of such material renders it imperative that it be subjected to heat for the purpose of placing the same in a semi-plastic condition in order to apply the same successfully to the head of a tack.

Such material is ordinarily provided in the form of cups or caps, into which the head of the tack may be fitted and the skirt portion of the cup or cap rolled or crimped around the periphery of the head of the tack.

In my present invention I have devised means for subjecting the cup to a heating operation for a relatively long period of time before the actual attaching operation takes place, with the result that the cup is in the proper semi-plastic condition prior to being acted upon by the attaching punch and die.

In carrying out my invention, I preferably prefabricate the caps of celluloid or equivalent material and likewise prefabricate the thumb tacks and place the caps and thumb tacks each in a separate magazine from which they are fed to a part of the machine where the cap is positioned in operative relation to a heating device and is carried intermittently onward toward the cooperating punch and die, and during such passage has associated therewith a thumb tack which is placed in position with its head within the cap. When the cap is positioned, and after the proper lapse of time to enable the cap to be brought to the proper semi-plastic condition, the associated cap and tack head are brought into association with cooperating punches and dies which roll or crimp the skirt of the cap about the peripheral edge of the tack head.

A feature of my invention is an improved device for applying ornamental caps to the heads of tacks.

A feature of my invention is an improved de-

vice for operatively associating a cap with a tack, to the head of which tack the cap is to be attached.

A feature of my invention is an improved device in which caps of celluloid or equivalent material are associated with a tack head, and wherein the cap is brought to a semi-plastic condition prior to the attaching of the cap to the head. 5

Other features will be apparent as the description of the invention progresses. 10

In the accompanying drawings, illustrating one form of my improved device—

Fig. 1 is a front elevation of a tack head capping machine.

Fig. 2 is a sectional plan view on the line 2—2 of Fig. 1. 15

Fig. 3 is a section on the line 3—3 of Fig. 1, illustrating the form of chute leading from the tack magazine to the tack positioning means.

Fig. 4 is a section on the line 4—4, of Fig. 1, 20 illustrating the chute leading from the cap magazine to the cap positioning means and illustrating the means for positively moving the caps along and through the chute.

Fig. 5 is an end elevation of the upper right hand end of Fig. 1. 25

Fig. 6 is a plan view of the drive mechanism shown at the lower left hand corner of Fig. 1, and illustrating the means for varying the speed of the power applying shaft. 30

Fig. 7 is a sectional elevation taken on the line 7—7 of Fig. 1.

Fig. 8 is a sectional detail of an enlarged scale showing an assembled cap and thumb tack in position relative to the attaching punch and die 35 and prior to the attaching operation.

Fig. 9 is a view similar to the view shown in Fig. 8 and showing the cooperating punch and die in position with respect to the cap and thumb tack at the completion of the cap attaching operation. 40

Fig. 10 is a plan view showing the platen of the machine and certain parts carried thereby, with the means, for positioning a tack in a cap in initial position. 45

Fig. 11 is a view similar to Fig. 10 and showing the tack positioning means in final position.

Fig. 12 is a section taken on the line 12—12 of Fig. 10 and

Fig. 13 is a section taken on the line 13—13 of Fig. 11. 50

Referring to the drawings, 10 designates the base of my improved machine having formed integral therewith at its upper end a table or 55

platens 11 of any desired shape, but preferably rectangular. At one end of the platen 11, the rear end as viewed in Figs. 1 and 7 is a bearing standard 12. In this bearing standard 12 are 5 aligned bearings 13, spaced apart from each other and in such bearings is rotatably mounted a shaft 14. At one end of the shaft 14 adjacent to the front bearing 13 is formed a crank arm 15 and at the other end of such front bearing 13 10 and on the shaft 14 is secured a collar 16. This construction prevents axial movement of the shaft 14 in its bearings.

The shaft 14 extends rearwardly beyond the rear bearing 13 and at its rear end has secured 15 thereto a hand wheel 17 and by means of which shaft 14 may be rotated manually in either direction. Adjacent to the hand wheel 17 and keyed to the shaft 14 so as to be rotatable therewith but slidably axially thereon is a sleeve 18, 20 to the front face of which is attached a clutch member 19. On the shaft 14, between the clutch member 19 and the rear bearing 13 is a sleeve 20, 25 such sleeve being rotatably mounted on the shaft 14. Formed integral with the sleeve 20 is a V-pulley 21, and attached to such sleeve adjacent to the clutch member 19 is a pulley 22, 30 such pulley having a face 23 thereof cooperating with the clutch member 19.

Secured to one of the side faces of the platen 30 11 in any convenient manner is a bracket 24, in which is secured a shaft 25. On the shaft 25, and within the limits of the bracket 24, is rotatably mounted a sleeve 26 through which extends a set screw 27 and by means of which the sleeve 35 26 may be adjustably secured to the shaft 25. Extending radially outward from the sleeve 26, in alignment with each other, are spaced arms 28 such arms being provided at their outer ends with aligned bearings 29. In the bearings 29 is 40 rotatably mounted a shaft 30 to which is secured, between the bearings 29, a pulley 31.

The pulley 31 is in alignment with the pulley 22 on the shaft 14 and over such pulleys runs a driving belt 32. Secured to one end of the shaft 45 30 is a friction disk 33, which is engaged by a friction cone 34, carried by the drive shaft of a prime mover, such as an electric motor 35. The motor 35 is adjustably mounted on a base 36, which in turn is adjustably mounted on the shaft 25.

By properly adjusting the motor 35 on the base 36 any desired speed of rotation of the shaft 30 and therefore the pulley 22 may be obtained. When power is applied to the motor 35 it is apparent that the pulley 22 and sleeve 20 will rotate 55 freely on the shaft 14.

Associated with the sleeve 18 is the forked end 37 of an arm 38 of a bell crank lever which is pivotally mounted on a shaft 39 secured to a bracket 40 attached to or formed integral with the platen 11. The other arm 41 of such bell crank lever is pivotally attached at its free end to the upper end of a clutch trip rod 42 which extends downwardly to a treadle (not shown). 60 This is the usual construction in this type of machine. Downward movement of the clutch trip rod 42 will rotate the bell crank lever about the shaft 39 and will cause a movement of the clutch member 19, axially of the shaft 14 toward and into engagement with the clutch face 23 of the pulley 22, and therefore the power transmitted from the motor 35 to the pulley 22 will be utilized to rotate shaft 14 in the proper direction.

Formed on the vertical face of the standard 12 75 is a vertically arranged slideway 43 in which is

slidably mounted a ram or plunger 44 carrying at its lower end a forming die 45 which will be hereinafter described in detail. Secured to the rear face of the ram or plunger 44 by screws 46, are cam plates 47 and 48, spaced apart from each other to define a cam race 49, in which works a cam roller 50, carried by the crank arm 15 on the shaft 14. This cam race 49 is so formed as to permit reciprocatory movement of the ram or plunger 44 in the slideways 43. 10

The shape of such cam race 49 is clearly shown in dotted lines in Fig. 1, and on inspection of such figure it will be noted that the ram or plunger 44 is in its uppermost position and that as the shaft 14 rotates the cam roller 50 will move the 15 ram or plunger 44 downwardly until the said ram or plunger is in its lowermost position and will maintain such ram or plunger in its lowermost position until the cam roller 50 has moved from one end of the lower curved portion of the 20 cam race 49 to the other end of such curved portion of the cam race.

Upon continued rotation of the shaft 14 of the cam roller 50 will engage with the centrally arranged downwardly extending portion of element 25 47 and will cause a sudden upward surge of the ram or plunger 44 until the same has reached its uppermost position. The movement imparted to the ram or plunger 44 therefore is a relatively slow downward movement from its highest to 30 its lower point, a maintenance of the ram or plunger at its lowermost position for a relatively long period of time, and a quick return of the ram to the highest point. The object of such movement will be described in detail hereinafter. 35

Mounted on the drive shaft 14 is a cam 51. Formed integral with the standard 12 and at the rear thereof is a boss or lug 52, provided with a vertical perforation which is in alignment with a perforation in the table or platen 11 such perforations being lined with an anti-friction metal sleeve. Slidably mounted in the perforation in the boss or lug 52 and in the perforation in the platen 11 is a shaft 54. Secured to the top end of the shaft 54 is a bearing member 55 which is 45 provided on its inner end with a fork 56 through the members of which extends a shaft 57. On such shaft between the members of the fork 56 is rotatably mounted a cam roller 58 which is normally in engagement with the cam 51. Rotation 50 of the main drive shaft 14 therefore, through the cam 51 will cause a vertical reciprocatory motion of the shaft 54 in its bearings.

Secured to the shaft 54 between the top face of the platen 11 and the boss 52, by a screw 59, is 55 a collar 60. Between the collar 60 and the upper face of the platen 11 and surrounding the shaft 54 is a coil spring 61, which tends to keep the shaft 54 in its uppermost position with the cam roller 58 always in engagement with the cam 51. 60

The cam 51 is shown in Fig. 7 with the cam roller 58 in engagement with a portion of its surface. This surface, with which the cam roller 58 is at present in engagement, is substantially cylindrical and that portion of the cam 51 shown 65 above the main drive shaft 54 is substantially flat, and represents a segment of a cylindrical cam. Therefore, the shape of the cam 51 is such as to cause a downward movement of the shaft 54, until the cam roller engages with 70 the cylindrical portion of such cam, whereupon the shaft 54 will be maintained stationary and in its lowermost position, until the cam roller 58 rides off the cylindrical portion, whereupon such shaft 54 will have imparted thereto, a rela- 75

tively rapid upward movement, due to the tension in the coil spring 61. In its uppermost position, the cam roller 58 does not engage with the cam roller 51 and therefore means are provided for limiting the upward movement of the shaft 54.

This means comprises the following instrumentalities: Secured to the shaft 54 by screw 62 is a lug 63, provided with a vertically arranged threaded hole through which is screwed the threaded portion of a stud 64. On the threaded portion of the stud 64, below the lug 63 is screwed a lock nut 65, which adjustably holds the stud 64 in adjusted position relative to the lug 63. The stud 64 is provided with an integrally formed multi-sided portion 66, to receive a wrench and by means of which the stud 64 may be rotated for adjustment purposes. The upper part of the stud 64 is slidably mounted in a hole formed in the boss 52 and the engagement of the upper end 20 of the stud 64 with the bottom of the hole, limits the upward movement of the shaft 54.

Secured to the top face of the platen 11, in any convenient manner, is an arcuate shaped stationary block 67, provided on its upper edge with a rabbet or track 68 for purposes to be hereinafter described. Formed in the stationary block 67 and in the table or platen 11 and in alignment with each other, is a vertical perforation in which is slidably mounted a bottom plunger 69. The lower end of the bottom plunger 69 is reduced in diameter and threaded to receive the adjusting nuts 70 between which is positioned one end of an arm 71. The other end of this arm 71 surrounds the lower end of the shaft 54 and is rigidly and adjustably secured thereto by means of the bolt 72. Therefore, as will be apparent from a study and inspection of Fig. 7, and assuming the main drive shaft 14 to be rotating, the cam 51 engaging with the cam roller 58, will maintain the upper end of the bottom plunger 69, substantially in the plane of the bottom of the rabbet or groove 68 in the upper surface of the stationary block 67, as shown in Fig. 8. This condition will prevail until the cam roller 58 rides off the cylindrical portion of the cam 51, whereupon the spring 61 will force the bottom plunger 69 upwardly and into the position shown in Fig. 9 where it will be held with a yielding pressure determined by the strength of the spring 61. Also, it will be apparent from an inspection of Fig. 7, that with the top of the bottom plunger 69 in the position shown in such figure that the lower end of the upper plunger 45 will be in its uppermost position, or in the position shown in Fig. 8, and that when the main drive shaft 14 has rotated to bring the cylindrical portion of the cam 51 out of engagement with the cam roller 58, the crank arm 15 will be in a position 180° removed from its position shown in Fig. 7 and therefore at such time the cam roller 50, engaging with the cam race 49, will have moved the cross head 44 and therefore the top plunger 45 to its lowermost position or into the position indicated in Fig. 9. The particular operation to be performed on the materials being worked upon by the top and bottom plungers 45 and 69 respectively, will be described more in detail hereinafter.

Secured in a vertical perforation in the table or platen 11 and extending upwardly from the upper face thereof is a shaft 73. This shaft lies in the center or axis of the arcuate stationary block 67. Rotatably mounted on the shaft 73 on the top face of the platen 11 is a ratchet 74. Secured to the top face of the ratchet 74 by

screws 75 is a notched plate 76, the peripheral notched portion of which rides on the face of the rabbet or track 68 in the stationary block 67. The notches in such plate 76 are indicated by the reference numerals 176 and are of such dimensions 5 as to permit the lower bottom plunger to slide therethrough, as shown in Fig. 9. Rotatably mounted on the shaft 73 and resting on the top of the notched plate 76 is a circular plate 77.

Formed integral with the circular plate 77 and 10 extending radially outward therefrom is an arm 78 which has secured therein a stub shaft 79 which extends downwardly from the under face thereof. Rotatably mounted on the stub shaft 79 and secured thereto by screw 80 is a driving 15 pawl 81, which engages with the ratchet wheel 74, for intermittently rotating the same in a counter-wise direction as viewed in Figs. 1, 10 and 11.

Formed integral with the platen 11 on the upper face thereof is a boss 82, through which is threaded a stud 83 and which stud is engaged by the end of the driving pawl 81 to limit the forward movement of such driving pawl. The stud 83 is adjustable in the boss 82 and after adjustment is held firmly in position by means of the locking nut 84, as shown in Figs. 10 and 11. The spring 65 constantly urges the driving pawl 81 into engagement with the teeth of the ratchet 74.

Secured to the upper end of the shaft 73, in any convenient manner, is a notched collar 86, which receives one end of a spring 87 surrounding the shaft 73 between the collar 86 and the top surface of the plate 77, and the other end of such spring 87 engages in a perforation 188 in the plate 77. 35 The spring 87 is tensioned to constantly urge the plate 77 to rotate in a clock-wise direction, as viewed in the drawings and thereby always tends to bring the driving pawl 81 into operative position with respect to the ratchet 74. 40

Secured to the upper face of the table or platen 11 is a stub shaft 88 and rotatably mounted on such stub shaft is a holding pawl 89, a spring 90 maintains the holding pawl always in operative relation with respect to the ratchet wheel 74 and 45 prevents backward movement thereof so that the ratchet wheel and apparatus carried thereby always rotates in a counter-clockwise direction, as viewed in the drawings. Also formed integral with the platen 77 and extending radially outward therefrom is an arm 91 in which is rotatably mounted a stub shaft 92 formed on the lower end of a universal or socket bearing member 93.

Formed integral with the standard 12 on the forward face thereof and adjacent to the slide-way 43 is a bearing standard 94 provided with a shaft 95, such shaft being secured thereto by nut 96. Rotatably mounted on the shaft 95 is a lever 97 which extends downwardly and has at its lower end a spherical head or knob 98 which rests in the socket member 93. Secured to the shaft 95, at the end remote from the bearing member 94, is a disk 99, provided with a notch to receive one end of a coil spring 100, which is fixed to and surrounds the stationary shaft 95, 65 and the other end of this spring engages in a hole in the lever 97. The spring 100 is so placed as to constantly urge the lower end of the lever 97 toward the standard 12, as shown in Fig. 7, or in other words, to constantly urge the plate 77 to 70 rotate in a clock-wise direction as viewed in Figs. 10 and 11, specifically.

Rotatably mounted on a shaft 101 secured to the side of the lever 97, and intermediate the ends of such lever, is a cam roller 102, which is 75

always in engagement with a screw 101 upon which is mounted a cam plate 103. The cam plate 103 is secured to the front face of the cross head 44 by screws 104. As the spring 100 always keeps the cam roller 102 in engagement with the cam plate 103, it is apparent that an oscillatory motion will be imparted to the lower end of the lever 97 by the reciprocatory motion of the cross head 44, and this oscillatory motion of the lever 97 will impart an oscillatory motion to the plate 77 on the shaft 73, resulting in an intermittent step-by-step rotary movement being imparted to the ratchet 74 by the driving pawl 81, and because of the presence of the holding pawl 89, no retrograde movement of the ratchet wheel 74 can take place.

The mechanism above described as being on the upper surface of the table or platen 11 and comprising the stationary block 67 and rotary notched plate 76, and plate 77 are utilized in connection with material feeding means to position the material as it is received from the various magazines which deliver the material to the upper and lower plungers 45 and 69, respectively, where the assembling operation takes place, after which the assembled material is fed to a discharge chute.

The material to be operated upon comprises the usual well known metallic thumb tack, and caps of celluloid or similar material to be attached thereto, but obviously the invention is adapted for the capping of a large number of articles other than a thumb tack. Therefore, the description of my improved machine, while it is given in connection with the operation of placing caps on thumb tacks, such described operation is for illustrative purposes only, and I am not to be limited in the interpretation of claims covering the novel features of my machine to its use as a tack capping 40 instrumentality only.

Preferably, I arrange the magazines for holding the material to be fed to the various instrumentalities carried by the platen 11, so as to take advantage to as great an extent as possible of the force of gravity to assist in feeding material to the point of delivery. In the case of the caps, however, I do not depend entirely on the force of gravity for feeding the same to the point of delivery, but in addition thereto utilize compressed 50 air, to positively force the caps along the chute leading from the cap magazine to the point of delivery.

The magazines referred to are mounted on the top of a bracket 105, which is secured, as by the bolts 106, to the table or platen 11. Such bracket 105 is preferably located at one side of the table or platen 11 so as to leave the front of the mechanism carried by the platen 11 accessible for inspection, adjustment, repair and replacement. Bolted to the upper surface of the bracket 105, is a bracket 107 and at the other end of the bracket 105 is secured a bracket 108. On the bracket 107 is to be mounted the magazine for the tacks, while on the bracket 108 is to be mounted the magazine for the cups or caps.

Referring specifically to the bracket 107, there is formed therein a bearing 109 in which is rotatably mounted a shaft 110. Secured to the inner end of the shaft 110 is a friction plate 111, while 70 secured to the outer end of such shaft is a hollow, relatively cone shaped, open ended tack magazine 113, having its larger end flanged as indicated by the reference numeral 114, and such flanged larger end is seated in a recess 115 formed in the outer face of the bracket 107. Formed integral

with the bracket 107 and at the inner top end thereof is a funnel or hopper 116 which extends through the wall of the bracket 107 and into the space within the cone shaped magazine 113. This funnel or hopper 116 is utilized to receive the tacks, and to guide the same into the magazine 113.

At the lower end of the outer face of the bracket 107 and leading into the cone shaped magazine 113 is an exit chute 117, through which the tacks 10 are fed. Secured to the exit chute 117 is a discharge track or trough 118 which has its exit end terminating adjacent to the track 68 in the upper inner surface of the stationary block 67, as clearly shown in Fig. 13. The flange 114 of the magazine 113 is provided with a plurality of spaced slits 120 and such slits, as the magazine 113 rotates, will engage with the shank end of individual tacks 119 from the plurality of the tacks in the magazine 113, and will feed the same to the exit chute 20 117, through which they will fall by gravity into the track or trough 118 which may be of any desired form, but preferably of the form shown in Figs. 11 and 13, where it will be noted that the main portion of the trough or track 118 has a 25 groove 121 therein large enough to easily and comfortably receive the head of the tack 119, and that plates 122 are secured to the track 118 by screws 123 to define the space between them sufficiently wide to permit the tacks 119 to move easily 30 along the track and prevent the heads of such tacks from falling out of the track 118.

The magazine for the caps or cups 130 is quite similar to the magazine for the tacks and comprises a cone shaped magazine 124, secured to the 35 rotating shaft 125, mounted in the bracket 108 and provided on its inner end with a friction plate 126. There is connected with and forming part of the bracket 108, and therefore the magazine 124, a funnel or hopper 127 through which the caps or 40 cups 130 pass to enter the rotating magazine 124. Also, there is provided an exit chute 128 at the lower end of the bracket 108, which cooperates with a plurality of depressions 129, formed in the material at the open end of the magazine 124, 45 such depressions being of a size to receive the cups 130, (see Figs. 10 and 12) and separate such cups from the plurality of cups within the magazine 124, thus delivering the same to the exit chute 128.

Secured to exit chute 128 is the upper end 50 of a chute or track 131 which extends downwardly and has its lower end terminating adjacent to the track 68 on the arcuate block 67, as clearly shown in Figs. 10 and 12. The chute or track 131 is similar in construction to the track or chute 118 and is such as to permit the cups or caps to be arranged therein in succession and to be freely movable or slid able therein and prevented from accidental removal therefrom.

Because of the extremely light character of the material of the caps or cups 130 and particularly because of the extreme lightness of each individual cap or cup, I find it preferable to utilize mechanical means for assisting the separation of the caps 130 from each other within the magazine 124, and at the point of exit 65 128, as well as to mechanically assist in the passage of the caps or cups downwardly along the track or chute 131. Preferably, this mechanical means takes the form of air under pressure, and for this purpose I have utilized an air compressing means, mounted on and driven by the driving mechanism of the capping device. It will be possible and sometimes desirable to utilize air 70 75

pressure from a source remote from the machine but I preferably utilize the means shown in the drawings, as I am enabled to obtain the exact degrees of pressure—which is relatively small—
5 which is necessary to feed the caps or cups 130 along the track 131.

This means comprises an air pump 132 mounted on a bracket 133, secured to the table or platen 11. The piston rod 134 of the air pump 10 extends upwardly and is secured by nuts 135 to an arm 136, in turn secured to and driven by the cross head 44. At the exhaust end of the air pump 132 are air pipes 137, 138 and 139. The pipe 137 leads to the funnel or hopper 127. 15 The pipe 138 leads to a point adjacent to the magazine 124, just above the discharge chute 128 thereof. The pipe 139 leads to a nozzle 140 arranged at the lower end of the track 131 adjacent to the juncture thereof with the arcuate stationary block 67, which I have found to be the best position to mechanically urge the caps or cups 130 into operative position with respect to the instrumentalities employed to position of the same relative to the tacks 119.

20 In the brackets 107 and 108, and at opposite ends of the bracket 105 is arranged a bore 141 in the bracket 107 and a bore 142 in the bracket 108. In the bore 141 is slidably mounted a bar 143 and in the bore 142 a bar 144 is slidably mounted. The outer ends of the bars 143 and 144 are forked, as shown in Fig. 1, to receive bearing members 145 and 146, in which is rotatably mounted a shaft 147. Such shaft 147 has secured thereto friction disks, one of which, the friction disk 148, engages with the friction plate 111 and the other, the friction disk 149, engages with the friction plate 126. Secured to the shaft 147, adjacent to the bore 141 is a V-pulley 150, which is in alignment with the V-pulley 21, formed on the collar 20 and over the pulleys 21 and 150 runs a belt 151. This mechanism is utilized to rotate the shafts 110 and 125 of the tack and cap magazines respectively, and the rate of rotation of the shafts 110 and 125 may be adjusted by altering the relative position of the friction disks 148 and 149 with respect to axes of rotation of the friction plates 111 and 126.

25 The ratchet wheel 74 is intermittently rotated step-by-step by means of the driving pawl 81, as above described, and at the end of each intermittent step-by-step movement the ratchet wheel 74 is held stationary by the holding pawl 89. The notched wheel 76 is so positioned relative to the teeth of the ratchet wheel 74, and so positioned relative to the exit end of the chute 131 for the cups 130, that such cups 130 will move in succession out of the chute 131 and into the notches in the notched plate 76 as such plate 30 is intermittently rotated. In other words, the normal position of the notched plate 76 with respect to the exit end of the chute 121, is shown in Fig. 11, where it will be seen that the cup 130 at the exit end of the chute 131 will have been fed into a notch 176 in the notched plate 76, which is now in alignment with such chute 131.

35 As the plate 77 is oscillated on the shaft 73, the driving pawl 81 will engage with the ratchet wheel 74 and will rotate the notched plate 76 in a counter-clock-wise direction, rotating the same from the position shown in Fig. 11 to that shown in Fig. 10, where it will be apparent that the cup 130 above referred to will have been moved in a counter-clock-wise direction a distance equal to the space of one tooth of the

plate 76, thus permitting the next succeeding notch 176 in the notched plate 76 to be moved into alignment of the exit end of the chute 131, whereupon the then lowest one of the cups 130 will move into the aligned notch 176. 5

It will thus be apparent that as an intermittent step-by-step rotary movement, in a counter-clock-wise direction, is imparted to the plate 76 the notches 176 will be successively filled by the cups 130, and such cups will be moved along the 10 rabbet 68 in the stationary block 67 from the exit end of the chute 131, as shown in Figs. 10 and 11, to the perforation 152 formed in the table or platen 11, whereupon the cups 130 will successively drop off the rabbet 68 and out of 15 the notches 176 in the notched plate 76 and into and through the perforation 152.

20 It will be apparent that this intermittent step-by-step movement of the notched plate 76 with respect to any particular cup 130 occupies a considerable space of time, and such time is utilized to place the cups 130 in a semi-plastic condition, in order that they may be successively and successfully operated upon by the dies and punches 25 without injury to the material of which they are composed. I accomplish this in the following manner:

25 The stationary block 67 is bulky and of solid and preferably ferrous material such as iron. At the end thereof and adjacent to and beneath the chute 131 a hole 153 is provided and such hole acts as a receptacle for holding the heater element 154, preferably of the electric resistance type and power for heating the same is obtained from a suitable source of power (not shown) by 30 means of the conductors 155. This heater 154 has been found amply sufficient to maintain the stationary block 67 at the proper temperature to satisfactorily condition the cups 130 in their travel along the rabbet 68 from the chute 131 to 35 the perforation 152. I am not to be limited to a single heater as shown in the drawings, and particularly in Fig. 12, but may utilize two or more of such heaters as may be considered desirable or necessary. 40

45 The chute 118, through which is fed by gravity the thumb tacks 119, in succession, as shown in Figs. 1, 10, 11 and 13, is positioned between exit end of the chute 131 and the positions of the bottom plunger 69 and the top plunger 45. 50

55 Secured to the oscillating plate 77 by screws 156 is a plate 157, folded over upon itself at 158 as shown in Figs. 10, 11 and 13 and the folded over portion is cut away, as indicated by the reference numeral 159. Referring specifically to Fig. 13, it will be noted that the upper edge of the outer end 158 is in position to be engaged by the pin portion of a thumb tack 119 and holds the head portion of such particular tack out of registry with the rabbet 68, as clearly shown in Fig. 13. Also the lower edge of the outer end of 60 158 is concentric with the peripheral edge of the oscillating cylindrical plate 77 and defines, with such plate 77, a passageway or guide for guiding the thumb tack 119, with the pin portion 65 thereof extending upwardly, as shown in Fig. 13. The lower end 159 is provided with a bias-cut 160. This bias-cut is shown in Figs. 10 and 11, and its entrance end is shown to be in alignment with the pin portion of the thumb tack 119 when the plate 157 is in the position shown in Fig. 10, at this time such bias-cut 160 is in a position to engage with one of the pin portions of the tacks 119 and to force such tacks 70 downwardly to the exit end of such bias-cut as 75

the plate 157 is moved from the position shown in Fig. 10 to the position shown in Fig. 11, where it will be seen that the tack 119 being then operated upon has its head portion positioned within one of the caps or cups 130 which rests in one of the notches of the notched plate 76.

The cylindrical oscillating plate 77 has its peripheral edge supporting the tack portion of the tacks 119 and such supporting peripheral edge 10 is made available until the tack 119, positioned within the cup 130, is positioned relative to the upper and lower plungers 69 and 45 respectively. The cylindrical plate 77 is rotatable with respect to the notched plate 76 and on reference to Fig. 15 it will be noted that the peripheral edge of the plate 77 supports the tack 119 prior to the operation of attaching the cup 130 thereto. The peripheral edge of the plate 77 is cut away as indicated by the reference numeral 161, for the purpose of providing clearance for the upper and lower plungers above referred to. As the plate 77 moves from the position shown in Fig. 10 to the position shown in Fig. 11, it will be noted that a clear passage is afforded by the cut away portion 161 for the upper plunger 45.

At this particular instant, the main drive shaft 14 is in the position shown in Fig. 7, with the crank 15 in its uppermost position and with the cam 51 in such a position that the cylindrical portion thereof is in its lowermost position. As a consequence, the cross-head 44 is in its uppermost position and therefore the upper plunger 45 is in its uppermost position, or in the position shown in Fig. 7, and particularly in Fig. 8. Also, because of the position of the cylindrical portion of the cam 51, the shaft 54 is in its lowermost position and therefore the lower plunger 69 is in its lowermost position, with the upper surface thereof substantially coincident with the rabbet 68, as shown in Fig. 8. Also, the plate 40 77 has been rotated through the space of one tooth so as to bring a cup 130 and a tack 119 nesting therein into position at the top end of the lower plunger 69, as shown in Figs. 8 and 10.

The main shaft 14 continuing to rotate will 45 bring the cam roller 50 into engagement with the cam race 49 in such a manner as to move the cross-head 44 downwardly. Such rotation also rotates the cam 51 with respect to the cam roller 58. As the cross head 44 moves downwardly, the 50 cam roller 102 on the arm 97 will ride down on the cam block 103, so as to cause rotation of the plate 77 in a clock-wise direction and such plate from the position shown in Fig. 10 to the position shown in Fig. 11. Referring to Fig. 11, it 55 will be apparent that the cut-away portion 161 completely exposes the cup 130 and tack 119, and that the material of the plate 77 is out of the line of travel of the upper plunger 45, which moves downwardly from the position shown in Figs. 7 and 8 and toward the position shown in Fig. 9. As the shaft 14 continues its rotation and the top plunger 45 approaches its lowermost position, or the position shown in Fig. 9, the cam 60 roller 58 will ride off the cylindrical portion of the cam 51, whereupon the spring 61, surrounding the shaft 54, will move such shaft upwardly, causing simultaneously an upward movement of the lower plunger 69, which thereupon moves from the position shown in Fig. 8 to the position shown 65 in Fig. 9. Such movement causes the peripheral edge of the skirt portion of the cup 130 to be crimped or curled about the peripheral edge of the tack 119, being assisted in performing such operation by the pattern cut on the lower end 70 of the upper plunger 45.

The top plunger 45 is provided with an axial bore in which is slidably mounted a plunger 45a provided with a bore 45b which when the plunger 45 is moved downwardly from the position shown in Fig. 8 to the position shown in Fig. 9 will allow 5 the pin portion of the thumb tack 119 to be housed therein as clearly shown in Fig. 9. The plunger 45a is resiliently mounted in the plunger 45 by means of a spring 45c and which spring constantly urges the plunger 45a downwardly to 10 the lowest limit of its movement. This mounting of the plunger 45a will permit the same to move upward relative to the plunger 45 as the plunger 45 moves downward into engagement with the bottom plunger 69, as clearly shown in Fig. 9. 15

As the main drive shaft 14 continues to rotate, the cam roller 50 will cause an upward movement of the cross head 44 and the cam plate 103 thereon will engage with the cam roller 102 and rotate the circular plate 77 from the position shown 20 in Fig. 11 to the position shown in Fig. 10, this movement also moving the notch of the notched plate 76 into registry with the hole 152, so as to allow the cap or cup 119 to drop into the hole 152. Before the edge of the cut away portion 161 25 of the circular plate 77 reaches the space occupied by the upper and lower plungers 45 and 69, as viewed in Fig. 9, the cylindrical portion of the cam 51 will have engaged with the cam roller 58 to cause a downward movement of the shaft 54 30 and a corresponding downward movement of the bottom plunger 69 into its lowermost position or into the position shown in Fig. 8. Practically simultaneously therewith, the cam roller 50 engaging with the proper portion of the cam race 35 49 will cause an upward movement of the cross head 44 a sufficient distance to cause the upper plunger 45 to move into its uppermost position, or into the position shown in Fig. 8. Therefore, there will be no conflict between the cylindrical 40 plate 77 and either of the upper or lower plungers 45 and 69 respectively.

Assuming the device to have been constructed and arranged as above described and that it is desired to attach to the heads of the thumb tacks 45 119, the cups 130 of celluloid or other similar or equivalent material, the operator will place a quantity of thumb tacks in the magazine 113 and a quantity of cups 130 in the magazine 124 and will adjust the discs 148 and 149 relative to 50 the discs 111 and 126 respectively so as to have the rotating portions of the magazines 113 and 124 rotate at the proper speeds and in the proper direction. Also, the driving motor 35 is adjusted on its support 36, so as to maintain the proper 55 relation between the driving disc 33 and the driving disc 34, whereby to rotate the shaft 30 at the proper speed and to drive all parts of the mechanism, including the magazines 113 and 124, at the proper speed. Power is then turned into an 60 electric heater 154 through the conductors 155, the motor 35 placed in operation and the parts begin to function as above described.

Actually, the tacks 119 will be sorted out and will be placed in the track 118, as shown in Figs. 65 1, 10 and 13 and will move down the track 118 by gravity to the point shown in Fig. 11. Also, the cups 130 will be placed in the proper position relative to the track 113 and will be forced downward therein partly by gravity and partly by 70 air from the jets 140. As the main drive shaft 14 rotates, the circular plate 77 will have imparted thereto an oscillatory movement, taking up in the notches 176 thereof at each step a cup 130, shown in Figs. 10 and 11 and above described 75

and such cups 130 will be properly tempered and brought to a semi-plastic condition by the now heated stationary block 61. By means of the plate 157, the tacks 119 are positioned properly 5 with respect to the cups 130 and move to the position shown in Figs. 8, 9 and 11 where, in the manner above described the cups 130 are folded and secured about the peripheral edge of the tacks 119. The tacks afterwards drop through 10 the hole 152 in the table or platen 11 into any desired receptacle.

Whereas, I have described my invention by reference to specific forms thereof, it will be understood that many changes and modifications 15 may be made without departing from the spirit of the invention.

I claim:

1. An improved tack capping machine comprising, a magazine for holding a plurality of 20 tacks, a magazine for holding a plurality of caps, means for agitating the tacks and the caps and feeding said tacks and caps successively out of their respective magazines, a chute for receiving the tacks as fed from the tack magazine, a chute 25 for receiving the caps as fed from the cap magazine, and means located at the exit ends of said respective chutes for arranging the caps each with the head of a tack deposited therein.

2. An improved tack capping machine comprising a heating element, means for positioning a cap thereon, means for positioning a tack head within said cap, means for moving said cap along the surface of the heating element, and means positioned at one end of the heating element for 35 attaching the cap to the tack.

3. An improved tack capping machine comprising a heating element, means for positioning a moldable material cap thereon at one end thereof, means for positioning the head of a tack 40 within the cup of moldable material, means for moving a cap and associated tack along the length of the heating element at a rate which permits the softening of the moldable material of the cap, and means arranged at the other end of the heating 45 element for crimping the skirt of the cup about the head of the tack.

4. In a tack capping machine the combination of a stationary block, a heating element associated with said block, a trackway in one face of said 50 block and extending throughout the length on such block, means for intermittently feeding cups of moldable material throughout the length of said track, said cups each having associated therewith the head of a tack, a movable upper 55 plunger arranged for reciprocatory movement at the exit end of the trackway, means for moving said plunger downwardly toward the trackway and maintaining said upper plunger in fixed relation to the trackway for a predetermined length of time, a bottom plunger and means for moving

the same upwardly toward the top plunger and under yielding pressure at the time the top plunger is maintained in its lowermost position, whereby said heated cap of moldable material has the peripheral skirt portion thereof rolled or crimped 5 about the peripheral edge of the head of the tack.

5. In an improved tack capping machine, a stationary block, a trackway formed in the upper surface thereof, a bottom plunger, means for positively moving the bottom plunger downwardly 10 with respect to the stationary block and holding its upper end substantially coincident with the bottom of the trackway for a predetermined length of time, means operable at the end of the predetermined time in the operation of the bottom plunger for moving the same upwardly under yielding spring pressure, a top plunger in axial alignment with the bottom plunger, means for holding the top plunger above the bottom plunger at and during the period of time when the bottom plunger is held in its lowermost position, and for positively moving the top plunger to and holding the same in its lowermost position during 15 the period of time when the bottom plunger is moved upwardly under yielding pressure. 25

6. An improved tack capping machine comprising, a magazine for holding a plurality of tacks, a magazine for holding a plurality of caps, means for agitating the tacks and caps and feeding the same out of their respective magazines, a chute for receiving the tacks as they are fed from the tack magazine, a chute for receiving the caps as they are fed from the cap magazine, means for positively feeding the caps along the 30 length of the chute, and means located at the 35 exit ends of the respective chutes for arranging a tack in each of the caps.

7. An improved tack capping machine comprising, a magazine for holding a plurality of tacks, a magazine for holding a plurality of caps, 40 means for agitating the tacks and caps and feeding the same out of their respective magazines, a chute for receiving the tacks as they are fed from the tack magazine, a chute for receiving the caps as they are fed from the cap magazine, air pressure means for positively feeding the caps along 45 the length of the chute and means located at the exit ends of the respective chutes for arranging a tack in each of the caps.

8. An improved capping machine comprising, means for receiving a plurality of caps in succession, means for receiving a plurality of tacks in succession and placing the same each in a separate cap, means for conditioning the caps by rendering them plastic, and means operating on such 50 conditioned caps for rolling or crimping the peripheral edge of the skirt portion of each cap about its associated tack head. 55

NILS H. ANDERSON. 60
